SIZING DEVICE FOR WINDING MACHINES

William C. Hanse, Philadelphia, Pa., assignor to American Viscose Corporation, Wilmington, Del., a corporation of Delaware

Substituted for abandoned application Serial No. 457,920, September 11, 1942. This application May 2, 1944, Serial No. 533,747

4 Claims. (Cl. 242—39)

This application is a substitute for abandoned application, Serial No. 457,920, filed September 11, 1942.

This invention relates to winding machines, and more particularly to an improved device for arresting the operation of the machine when the package being wound reaches a predetermined size.

The present invention is particularly directed to winding machines of the type generally disclosed in United States Patent No. 801,941, to Wardwell, wherein the yarn is wound upon a supporting element, such as a core, mounted upon a rotating spindle, the yarn being traversed longitudinally of the core by a thread guide which bears against the surface of the winding, and which swings away from the spindle as the wound package increases in size. The form of device for stopping the winding machine generally employed with this type of winding machine and shown in the Wardwell patent has the disadvantages of being somewhat slow-acting and of increasing the pressure of the thread guide against the surface of the winding as the package approaches the predetermined size to which the stopping device has been set. The slow-acting characteristic of the device results in wound packages of non-uniform weight and what is more important, the increased pressure on the package during actuation of the stopping device deforms the wound package.

It is an object of the invention to provide a novel form of device for automatically stopping the winding when the package reaches a predetermined size, which device avoids the exertion of undue pressure of the guide against the package. A further object is to connect the novel stopping device in a manner which will not cause it to interfere with the maintenance of operating conditions, in accordance with which the pressure of the traverse guide against the package gradually decreases as the package grows in size. Another object is to provide such a device which is simple in character, and which may be readily applied to standard machines without altering the structure thereof in any substantial way. Another object is to provide such a device which is adapted to co-operate with the mechanism for stopping the device automatically upon breakage or exhaustion of the supply of the yarn or strand being wound. A further object is to provide a device which is adjustable in character, so that a package of any desired size may be obtained upon the machine or machines to which the attachment is applied. Other objects and

advantages will appear from the drawing and description thereof.

In the drawing illustrative of the invention—

Figure 1 is a front elevational view of a conventional type of winding machine showing one embodiment of the present invention applied thereto;

Figure 2 is a side elevational view of the winding machine shown in Figure 1; and

Figure 3 is a perspective view of a modification of the invention with parts broken away.

While the invention will be described herein-after in relation to a particular type of conventional winding machine, it is to be understood that it is not limited to application thereto. In the description, the conventional parts of the winding machine will first be described and this will be followed by a description of the parts which constitute the present invention.

20 Referring to Figures 1 and 2 of the drawing, reference numeral 2 designates the fixed main frame of the machine. At the top of frame 2, a rotating spindle 3 is journaled in suitable bearings and is adapted to be driven by means of a 25 belt pulley or other suitable mechanism (not shown). The spindle is adapted to receive a cone or cop tube 4 upon which the package 5 is to be wound.

A shaft 6 is journaled in the frame 2 and extends in a direction parallel to the winding spindle 3. This shaft 6 is connected to the spindle and is driven therefrom by suitable means, such as gears, a belt and pulleys, or sprockets and chain, (not shown). The shaft 6 also carries a helical grooved cam 7 for rotation therewith.

A traverse frame 8 is pivotally mounted upon the shaft 6 upon which it is suitably balanced such as by the counterweight 9. This traverse frame 8 is provided with a backing plate 10 and 40 a porcelain bail 11 may be rotatably supported on a wire 12 whose depending legs adjacent the ends of the bail are suitably fastened within recesses in the plate 10 by means of set screws 13. The traverse frame 8 is constructed to provide a 45 horizontal groove through which a traverse bar 14 may reciprocate. A thread guide 15, whose upper end is adapted to press lightly against the package being wound is fastened to one end of the traverse bar 14 for reciprocation therewith.

50 The other end of the traverse bar 14 is provided with a head 16 having a depending pin or roller 17 adapted to engage the groove in the helical cam 7. As the package builds up, it gradually swings the traverse frame 8 away from the spindle 3 and the traverse frame is prevented from

swinging back toward the spindle by means of a lever 18 having one end fastened thereto at 19 and the other end engaging within a groove formed underneath a segment 20 which is pivotally fastened to the main frame 2 at 21.

The operation of the winding machine is controlled by a starting lever or handle 22, mounted on one end of a rotatable rod 23, supported in bearings at the top of the main frame 2. The opposite end of the rod 23 carries means for operating a clutch or similar device (not shown) to control the operation of the spindle 3 and the other parts of the machine driven therefrom. A lever 24 is mounted adjacent the starting lever 22 on the rod 23 so that it rocks therewith. One end of lever 24 is normally biased in a counter-clock direction by a spring 25 fastened to the frame 2 and is provided with a braking means 26 which is adapted to press against the spindle 3 and to stop the rotation thereof when the lever 22 is in the stop position, in which position the clutch or other device for operating the spindle 3 is disengaged. The other end of the lever 24 is formed as a curved arm having a hook 27 at its end. When the starting lever 22 is in operating position, in which the clutch is engaged with the spindle 3 and the brake is lifted therefrom (as shown in Figure 1) the hook 27 engages another hook 28 secured to or constituting part of the pivoted segment 20. The machine may be maintained in running position by setting these hooks 27 and 28 in opposition to the spring 25, which otherwise would tend to set the brake and to swing the starting lever 22 into the stop position.

The pressure exerted by the guide 15 against the exterior winding of the package is controlled by a counterweighted arm 29 pivotally mounted on a bracket 30 fastened to the frame 2 of the machine. The link 31 is connected to arm 29 a short distance from its pivotal axis and is connected to the traverse frame 8 at 32. For adjustment, the end of link 31 may be inserted into any one of a series of sockets 33 provided. It will be seen that as winding proceeds arm 29 swings in a counterclockwise direction and that this swinging of the counterweight causes a gradual decrease of the force exerted by link 31 tending to turn the traverse frame 8 in a counterclockwise direction.

A tension gate 34 of conventional construction is secured on bracket 30 and the tension exerted upon the yarn passing therethrough is controlled by a link 35 having one end attached to one of the grids of the tension gate 34 and the other end attached at 36 to a counterweighted arm 37 which is pivotally connected with the other arm 29. As the package grows in size, the arm 37 swings in a clockwise direction and thereby gradually reduces the tension exerted on the yarn by gate 34.

In operation of the machine, the yarn passes first through the tension gate 34 over the guide 30 of a slub catcher, under a break or exhaustion detector 38, over the porcelain bail 11 and through the traverse guide 15 to the package. The break detector 38 comprises a device pivotally mounted at 39 upon segment 20. The device is composed of two arms 40 and 41, one of which 40 extends toward a wheel 42 having numerous projections or ridges 43 thereon mounted upon the cam shaft 6 for rotation thereby. The other arm 41 is bent to form a horizontal extension 44 adapted to ride upon the yarn and along which the yarn may traverse to a certain extent. The extension 44 may be bent at the end to form a hook 45 to prevent the yarn from accidentally slipping out of engagement therewith. The first

arm 40 is of such length and the entire detector device 38 is so balanced that upon breakage of the yarn, the device swings in a clockwise direction to bring arm 40 into the path of the projections 43 upon the rotating wheel 42 which in turn forces the segment 20 in a counterclockwise direction sufficiently to release the two hooks 27 and 28 and thereby permit the spring 25 to throw the starting lever 22 into the stop position to apply the brake and disengage the clutch. A projection 46 on an arm 47 serves to limit clockwise motion of the arm 40 and indirectly arm 41 as will appear hereinafter.

The parts of the machine so far described are in the main part conventional and constitute no essential part of this invention except as will appear hereinafter. The arm 40 of the end breakage detector is independently pivotally supported at 48 on the pivotal mounting 49 upon which the other arm 41 is fixedly secured. A screw 50 secured to the pivotal mounting 49 of the end breakage detector serves as a rest for the arm 40 to limit its counterclockwise motion with respect to the pivotal mounting 49 of the end breakage detector.

In the form of the invention shown in Figures 1 and 2, an auxiliary arm 51 suitably secured to arm 29 for swinging motion therewith has a portion 52 arranged to engage arm 40 and to swing 30 it into the path of the projections 43 when the predetermined size of the package is attained, whereupon stoppage of the machine is effected. The arm 51 may be secured to arm 29 by means of a bolt 53, adjustability being provided for by 35 a slot 54 in arm 29. The arm 51 also may be provided with an indicator comprising the pointer 55 adapted to co-operate with the scale 56 upon arm 29. The scale may be graduated to correspond 40 with the sizes of packages that would be attained upon setting the pointer to the several indicia thereon.

Reference to the drawing will show that the application of the auxiliary arm 51 to arm 29 may readily be compensated for merely by 45 an adjustment of the counterweight on the arm 29.

In Figure 3, a modification is shown in which a metal strip 57 is fastened to the flat portion 58 of the saddle adjacent the pivot of the counterweight arm 29. Strip 57 has a bent portion 59 for supporting the arm 60, the upper end of which may be bent and is adapted to move the arm 40 into engagement with the ridged wheel 42 when a predetermined size of package is reached. The arm 60 is provided with a slot 61 to facilitate adjustment for obtaining different sizes of packages. Elements 46 and 47 of Figure 3 correspond in function to 46 and 47 of Figures 1 and 2.

From the description of the device, it is apparent that it is quick in action and involves only a slight amount of pressure for a relatively short time during the last part of the winding. It is simple in character, readily attachable to any 60 winding machine and is easily adjusted.

In the present specification and claims, the term "package" is used in a general sense to indicate any form of wound mass and the term "yarn" is intended to designate any kind of strand material whether textile or otherwise.

While a preferred embodiment of the invention has been disclosed, it is to be understood that changes and variations may be made without departing from the spirit and scope of the 70 invention as defined by the appended claims.

I claim:

1. In a winding machine, a winding spindle, a traverse mechanism, means for swinging said spindle and traverse mechanism relative to each other about an axis substantially parallel to that of the spindle as the winding proceeds, means for stopping said machine automatically comprising an arm arranged to be swung into engagement with an operating member of said machine to initiate the operation of said stopping means, a pivotally mounted counterweighted element connected to said traverse mechanism for controlling the pressure of the traverse mechanism against said package as the winding proceeds, and means associated with said element responsive to the growth of the package arranged to co-operate with said arm to initiate the operation of said stopping mechanism.

2. In a winding machine, a traverse frame, means for stopping said machine automatically comprising an arm arranged to be swung into engagement with an operating member of said machine to initiate the operation of said stopping means, a pivotally mounted counterweighted element connected to said traverse frame and means responsive to the growth of the package mounted on said element arranged to co-operate with said arm to initiate the operation of said stopping mechanism.

3. In a winding machine, a winding spindle, a traverse frame, a rotatable element, means for rotating said element, means for stopping said machine, a member having an arm movable into

engagement with said element to initiate said stopping means and having a second arm in engagement with the running course of yarn being wound, said member being normally withheld from movement to initiate operation of the stop means by said running course of yarn and being constructed to move of its own weight into engagement with said element to initiate the operation of the stop means upon breakage or termination of said yarn, said first arm being pivotally mounted with respect to said second arm, a pivotally mounted counterweighted element connected to said traverse frame and a member mounted on said element for motion therewith arranged for co-operation with said first arm to initiate the stopping means independently of said second arm.

4. In a winding machine, a traverse frame, a thread guide on said traverse frame, means for stopping said machine automatically comprising an arm arranged to be swung into engagement with an operating member of said machine to initiate the operation of said stopping means, means connected to said traverse frame for controlling the pressure of the guide against the package as the winding proceeds, and means responsive to the growth of the package associated with said pressure-controlling means and arranged to co-operate with said arm to initiate the operation of said stopping mechanism.

W. C. HANSE.
